UNITED STATES PATENT OFFICE.

ANTON MEYER, OF ST. LOUIS, MISSOURI, ASSIGNOR OF FIFTY-ONE ONE-HUNDREDTHS TO
JAMES W. ALLISON, OF ST. LOUIS, MISSOURI.

WIRE-GLASS-ROLLING APPARATUS.

No. 876,653.

Specification of Letters Patent.

Patented Jan. 14, 1908.

Application filed April 22, 1907. Serial No. 369,670.

To all whom it may concern:

Be it known that I, ANTON MEYER, a citizen of the United States of America, residing in the city of St. Louis and State of Missouri, have invented certain new and useful Improvements in Wire-Glass-Rolling Apparatus, of which the following is a full, clear, and exact description, reference being had to the accompanying drawings, forming part of this specification.

My invention relates to that class of glass rolling apparatus utilized for rolling sheets of glass with sheets of wire cloth embedded therein and examples of which are to be found in Letters Patent of the United States issued to me November 28, 1905 and January 23, 1906 and numbered respectively 805,657 and 810,786.

The present invention is in the nature of an improvement upon the apparatus shown and described in said patents and has for its object to improve the raising and lowering mechanism associated with the sheet pressure roll by which the wire cloth is delivered and pressed into the first layer of glass and the wire cloth shearing mechanism.

The present invention also has for its object to provide means for smoothing the surface of the top layer of glass after it is rolled.

Figure I is a side elevation of my improved apparatus. Fig. II is a view partly in end elevation and partly in vertical cross section of the end of my apparatus containing the wire cloth delivery and pressing mechanism. Fig. III is a longitudinal section taken through the parts illustrated in Fig. II. Fig. IV is a vertical section taken on line IV—IV Fig. III.

Referring to the accompanying drawings: 1 designates standards that are arranged in couples and which are adapted to receive the journal boxes of rolls 2 which may be raised and lowered by any suitable means, such as set forth in either of the Letters Patent hereinbefore mentioned.

3 is a carriage that is adapted to move to and fro upon suitable track rails beneath the rolls 2 and a remaining roll to be hereinafter mentioned, the said carriage serving to support a table 4 on which the glass is rolled.

5 are rack bars carried by the carriage 3 and extending longitudinally thereof, all of said parts having the same utility as corresponding parts in the patents mentioned.

6 designates a pair of standards located at 55 one end of the apparatus and disposed in alinement with the standards 1. These standards are provided with vertical guide-ways 7 in which are loosely mounted journal boxes 8 that are adapted to be raised and 60 lowered in said guide-ways.

9 is a pressure roll that is provided with spindles journaled in the journal boxes 8 and adapted to be rotated above the table 4 on the carriage 3. The spindles of this pressure 65 roll have fixed to them pinions 10 that are adapted to be placed in mesh with the rack bars 5 in order that they may act to impart rotation to said pressure roll upon reciproca- 70 tion of the carriage 3.

11 designates a delivery drum that is carried by a shaft 12 supported by means to be hereinafter mentioned in order that the drum may be raised and lowered with other parts of the apparatus. The drum 11 serves 75 to deliver wire cloth to the sheet of glass being rolled in order that it may be pressed into said glass by the pressure roll 9, the wire cloth being preferably supported in rolled form by a rod 12' that is mounted in bracket 80 arms 13 supported by the standards 6.

14 is a wire cloth straightening roller suspended by links 15 from the frame 6 and adapted to bear against the wire cloth while it is passing over the delivery drum 11. Ro- 85 tary motion is imparted to the wire cloth delivery drum by spur wheels 16 arranged in mesh with the pinions 10 on the spindles of the pressure roll 9 and spur wheels 17 carried by the spindles of the delivery drum 11. The 90 spur wheels 16 are carried by a shaft 18 supported by the same members that support the shaft of the delivery drum 11.

19 designates lift rods that are pivotally connected to the journal boxes 8 in which 95 the spindles of the pressure roll 9 are mounted and by which said journal boxes are raised and lowered in the guide-ways 7 of the standards 6 for the purpose of raising said pressure roll to any desired elevation above the 100 glass receiving table 4 or lowering it to the requisite position above the table for operation in rolling batches of glass placed upon the table and into which the wire cloth is pressed while the table is moving beneath 105 said pressure roll.

20 are segmental gears supported by rods 21 extending across the apparatus and

mounted in the standards 6 and to which the lift rods 19 are pivotally connected at 22.

23 are segmental gear levers, the teeth of which are arranged in mesh with the teeth of the segmental gears 20 and which are supported by rods 24 located opposite to said segmental gears. Each gear lever is provided with a lift pin 25.

26 designates lift rods in which the shafts 12 and 18 of the delivery drum 11 and the spur wheels 16 are journaled, the said rods including upper members 27 that are pivoted at 28 to their lower members in which said shafts are journaled and in the upper ends 15 of which upper members are vertical slots 29 that receive the lift pins 25 of the lever gears 23. The object in making this slot and pin connection between the lift rods 26 and the gear levers 23 is to permit vertical movement 20 of said lift rods independently of the lift rods 19 that support the pressure roll 9 for a purpose that will presently be made clear.

30 is a hand lever that is pivotally connected at 31, see Fig. II, to one of the standards 6 and 32 is a connecting rod pivoted to said hand lever and also to the gear lever 23 which parts it serves to unite, as seen in the last mentioned figure and in Fig. III.

33, see Fig. III, designates a stationary shear blade that is supported by the standards 6 at a point adjacent to the wire cloth delivery drum 11 and adjacent to the path of movement of the wire cloth in its travel from said delivery drum to the pressure roll 9 and 35 the table 4.

34 is a movable shear blade that is arranged in opposition to the stationary shear blade and which is adapted to be moved towards said stationary blade for the purpose 40 of severing the wire cloth into sheets of desired lengths as it passes over the delivery drum 11.

35 are bell crank levers pivotally connected at 36 to the standards 6 and each having one 45 of its arms arranged in engagement with the movable shear blade 34 while the other arm of each lever extends into juxtaposition with the lift rod 26 that is located at the side of the apparatus at which said lever is located.

50 Each of the lift rods 26 is provided with a stud or pin 37, see Fig. IV and dotted lines Fig. III, adapted to engage the adjacent arm of the bell crank lever 35 upon each upward movement of said rod for the purpose of actuating the lever and causing it to impart movement to the movable shear blade 34 for wire cloth cutting action. Each lift rod 26 is also provided with a socket 38 located near the lower end of the rod as seen in Fig. III.

60 39 are lift arms pivoted to the standards 6 at 40 and seated in the sockets 38 of the lift rods 26. 41 are dogs also pivotally supported at the point 40 and provided with heels 42 that extend beneath the lift arms 65 39. The dogs 41 are suspended in such

positions that they are adapted to be struck by trip blocks 3' carried by the carriage 3, see Fig. II, when said carriage has made a partial forward movement and the shears are to be brought into operation to cut the wire cloth passing between the shear blades. When the trip blocks strike the dogs said dogs are moved in a direction toward the lift arms 70 39 with the result that the heels of the dogs press against said lift arms and serve to elevate them, whereby the lift rods in turn are caused to actuate the bell crank levers 35 that move the shear blade 34 for cutting action and the wire cloth is severed as desired. 75

The lift rods 26, 27 being loosely connected to the gear levers 23 by slot and pin connections, said rods may readily move vertically in the wire cloth shearing actions without any movement being imparted 80 to said levers or to the lift rods 19 that support the pressure roll 9 and are adapted to be moved upon the actuation of the gear levers. When it is desired to elevate the pressure roll 9 and the wire cloth 90 delivery mechanism coöperating with said roll and carried by the lift rods 26, 27 the end lever 30 is depressed, thereby causing it to exert a pull upon the connecting rod 32. The gear lever 23 is then moved by the connecting rod and acts to lift the lift rods 26, 27 and through coöperation with the segment gear 20 causes said segment gear to be moved upwardly, thereby raising the lift rods 19 and the pressure roll and coöperating 100 parts are raised to a desired degree above the table 4. A reverse movement of the levers results in the parts just described being lowered to their former positions or to any degree of elevation that may be 105 desirable.

In rolling sheets of glass in the use of my apparatus a mass of molten glass is first placed upon the table 4 back of the pressure roll 9 and at a point adjacent to that at 110 which the wire cloth passes beneath said roll. Then, as the table moves forwardly during the rotation of said pressure roll which is driven by suitable means and geared to the carriage 3, the molten glass is 115 rolled into a lower layer with the wire cloth embedded therein. A mass of molten glass is placed upon the lower layer of glass and the wire cloth embedded therein and this mass is rolled into an upper layer by one of 120 the rolls 2 of the apparatus, thereby inclosing the wire cloth within the two layers of glass. The rolling operation is clearly illustrated in Fig. I of the drawings.

For the purpose of smoothing or ironing 125 out any wrinkles or ridges that may exist at the top surface of the sheet of glass as it is produced I provide an ironing member 43 that comprises a heavy block or plate, preferably of metal, extending entirely across 130

the space occupied by the sheet of glass being rolled and adapted to ride in contact with the upper surface of such sheet. This ironing member is supported at the proper elevation above the table 4 to contact to the desired degree with the sheet of glass by means of wheels 44 that are journaled, as seen in Fig. I. The table travels freely beneath the ironing member which is maintained in set position adjacent to the roll 2 that produces the final rolling action upon the sheet of glass and the ironing member is held in such position by means of arms or links 45 that are preferably fitted to the spindles of the roll last referred to and are adapted to permit a rise and fall motion of the ironing member.

I claim:

1. In a wire glass rolling apparatus, the combination of a carriage, a pressure roll surmounting said carriage, movable means supporting said roll, wire cloth delivery means, movable means supporting said wire cloth delivery means coöperable with said roll supporting means, and wire cloth shearing means operable by the means supporting said wire cloth delivery means, substantially as set forth.
2. In a wire glass rolling apparatus, the combination of a carriage, a pressure roll surmounting said carriage, movable means by which said pressure roll is supported, wire cloth delivery means arranged for co-operation with said roll, movable means by which said wire cloth delivery means is supported, and shearing mechanism operable through the medium of said means by which said wire cloth delivery means is supported, substantially as set forth.
3. In a wire glass rolling apparatus, the combination of a carriage, a pressure roll surmounting said carriage, vertically movable means by which said pressure roll is supported, wire cloth delivery means arranged for co-operation with said roll, vertically movable means by which said wire cloth delivery means is supported, and shearing mechanism operable through the medium of said means by which said wire cloth delivery means is supported; said means for supporting said wire cloth delivery means being susceptible of movement independent of said roll supporting means, substantially as set forth.
4. In a wire glass rolling apparatus, the combination of a carriage, a pressure roll surmounting said carriage, and geared thereto, a wire cloth delivery drum geared to said pressure roll, vertically movable means by which said drum is supported, wire cloth shearing mechanism associated with said drum supporting means, and means operable by said carriage whereby said drum supporting means is moved to operate said

shearing mechanism, substantially as set forth.

5. In a wire glass rolling apparatus, the combination of a carriage, a pressure roll, lift rods by which said pressure roll is supported, a wire cloth delivery drum coöperating with said pressure roll, lift rods by which said drum is supported, and lever mechanism connecting said pressure roll supporting and drum supporting rods, substantially as set forth.

75

6. In a wire glass rolling apparatus, the combination of a carriage, a pressure roll, lift rods by which said pressure roll is supported, a wire cloth delivery drum coöperating with said pressure roll, lift rods by which said drum is supported, and lever mechanism connecting said pressure roll supporting and drum supporting rods; said drum supporting lift rods being susceptible of movement independent of said roll supporting rods, substantially as set forth.

80

7. In a wire glass rolling apparatus, the combination of a carriage, a pressure roll surmounting said carriage, lift rods supporting said roll, gear members to which said lift rods are connected, a wire cloth delivery drum, lift rods by which said drum is supported, shearing mechanism operable through the medium of said last named lift rods, and levers connected to said last named lift rods, and coöperating with the gear members to which the first named lift rods are connected, substantially as set forth.

90

8. In a wire glass rolling apparatus, the combination of a carriage, a pressure roll surmounting said carriage, lift rods supporting said roll, gear members to which said lift rods are connected, a wire cloth delivery drum, lift rods by which said drum is supported, shearing mechanism operable through the medium of said last named lift rods, and levers connected to said last named lift rods, and coöperating with the gear members to which the first named lift rods are connected; said drum supporting lift rods 105 being movable independent of the levers to which they are connected, substantially as set forth.

100

9. In a wire glass rolling apparatus, the combination of a carriage, a pressure roll surmounting said carriage, a wire cloth delivery drum, lift rods by which said drum is supported, a pair of shear blades, one of which is movable, means coöperating with said lift rods for actuating said movable 115 shear blades, and means coöperating with said carriage for moving said lift rods, substantially as set forth.

110

10. In a wire glass rolling apparatus, the combination of a carriage, a pressure roll 120 surmounting said carriage, a wire cloth delivery drum, lift rods by which said drum is supported, a pair of shear blades, one of

125

which is movable, means coöperating with said lift rods for actuating said moving shear blades, and means coöperating with said carriage for moving said lift rods; said last named means comprising pivotally supported arms having engagement with said lift rods, and dogs engaging said arms and

operable through the medium of said carriage, substantially as set forth.

ANTON MEYER.

In presence of—

BLANCHE HOGAN,
LILY ROST.
